UNITED STATES PATENT OFFICE.

JAMES M. REYNOLDS, OF BUTTE, MONTANA.

STABILIZING DEVICE FOR AEROPLANES.

1,148,050.

Specification of Letters Patent. Patented July 27, 1915.

Application filed October 3, 1914. Serial No. 864,811.

To all whom it may concern:

Be it known that I, JAMES M. REYNOLDS, a citizen of the United States, residing at Butte, in the county of Silverbow and State of Montana, have invented certain new and useful Improvements in Stabilizing Devices for Aeroplanes; and I do hereby declare the following to be a full, clear, and exact description of the invention, such as will enable others skilled in the art to which it appertains to make and use the same.

This invention relates to flying machines, and has for its object to improve the means that have been heretofore proposed for stabilizing said machines.

With these and other objects in view, the invention consists in the novel details of construction and combinations of parts, more fully hereinafter disclosed and particularly pointed out in the claims.

Referring to the accompanying drawings forming a part of this specification, in which like numerals designate like parts in all the views, Figure 1 is a diagrammatic plan view, partly in section of a flying machine provided with a stabilizing means, made in accordance with my invention. Fig. 2 is an end elevational view of the parts shown in Fig. 1. Fig. 3 is a perspective view, diagrammatically showing one of the engines detached from the machine. Fig. 4 is a diagram illustrating the connections between the engines and the aviator's seat. Fig. 5 is a view similar to Fig. 1, but showing a slightly modified form of construction. Fig. 6 is an enlarged detail view showing the arm rest or back of the aviator's seat in two positions, and Fig. 7 is a slightly modified form of connection between the engine levers and the aviator's seat.

Any suitable supporting surfaces such as the upper and lower planes 1 and 2 may be employed, as well as any suitable frame work or bearing construction 3.

4 indicates the usual or any desired elevating plane, and 5 a rudder. The elevator 4, is provided with the rods 6 to which are attached the cords 7 leading to the steering wheel 8, and to the rudder 5 are attached 50 the cords 9, also leading to said steering wheel.

10 and 11 indicate an additional stiffening or frame work, and 20 suitable skids or other landing means.

All of the above parts are or may be of the usual or any desired construction, and

my invention will be understood from what is now to be described.

Pivoted in the frame 3, as at 12 are the trunnions 13 of a strap or casing 14 which contains the engine 16 having a shaft 17 to which is secured the driving and stabilizing propeller 18. Extending from the casing, and secured thereto as by the strap 19 is the operating lever 21, so that if said lever is lowered the engine and casing will rock on the trunnions 13, and the said propeller 18 will be raised. In the same way if the lever 21 is raised the engine and casing will likewise rock on the trunnions 13 to lower the propeller 18, as will be clear from the full and dotted line positions shown in Fig. 2.

It will be observed that since the framework 3 extends vertically as shown in Fig. 2, the propellers 18 are prevented from moving except in an up and down direction, so that when the propeller on one side is moved up or down it is compelled to move in a direction parallel to the propeller on the other side, which likewise moves up and down, and therefore a true stabilizing action is had, which would not be the case if only a single propeller mounted on gimbal bearings was provided, and which had a motion in all directions.

I prefer to employ two engines 16 symmetrically placed on each side of the center of the machine, as shown, and to cause their propellers 18 to rotate in opposite directions in order to counteract each other's disturbing forces which would otherwise tend to turn or tip the machine. I further prefer to locate the pivot points 12 of the engines in a line parallel to the supporting planes 1 and 2 and in a vertical plane passing through said supporting planes about one third of their width from their extreme forward edges 25, in order that the center of gravity of the system may be as near as possible below the center of buoyancy.

The seat for the aviator is represented at 26 having a pivoted back or arm rest 27, and leading downwardly from one of the levers 21 over the pulley 28, and to said back or rest 27 is the cord 30, see Fig. 4. Leading upwardly from said lever 21, over the pulleys 31, 32 and 33 to said arm rest 27 is the cord 34. Said cords 30 and 34 being attached to said seat back or arm rest 27, and the latter being pivoted as at 35, it is evident if it be swung from its full line to its

dotted line position, shown in Fig. 6, that the cord 34 will cause the lever 21 to rise and its corresponding propeller 18 to fall, while if the rest 27 is moved in an opposite direction, the lever 21 will descend through the pull on the cord 30, and its propeller 18 will rise.

In the same way, the other lever 40 of the other engine 16 is provided with a cord 41 passing downwardly over the pulley 42 to the rest 27, and also has a cord 43 passing upwardly over the pulleys 44, 45 and 46 and back to said seat rest 27. It therefore follows that as the rest 27 is moved toward the right as seen in Fig. 6, not only will the lever 21 be raised and its propeller 16 be lowered, but the lever 40 will at the same time be lowered and its corresponding propeller 16 be raised. It follows, likewise, if the seat rest 27 be turned toward the left as seen in Fig. 4, the lever 16 will be lowered and the lever 40 be raised, causing the propeller corresponding to lever 40 to be lowered. In other words, it will now be clear that if the supporting planes 1 and 2 be tipped on one side or the other, that the aviator may readily lean toward the high side, whereupon the lever 16 or 40 on said high side will be at once raised and its corresponding propeller be tipped or lowered in such a direction as will cause a portion of its power to be exerted in pulling down said high side. It will also now be clear that the same movement of the arm rest 27 toward the high side will cause the lever 40 or 16 on the low side to be lowered and its corresponding propeller to be tipped in such a direction as to cause a portion of its energy to be exerted in raising said low side. It therefore follows that by the simple expedient of locating and pivoting my engines and propellers as above disclosed, the propellers may be employed as stabilizers for the machine while at the same time propelling it forward.

In the modified form of construction illustrated in Fig. 5, the arrangement of parts are constructed as disclosed above, but the propellers are placed on the opposite side of the supporting planes and the aviator's seat is likewise placed on the side opposite to that shown in Fig. 1. Otherwise the construction is the same. In said figure, the lead of the cords from the levers 21 and 40 is necessarily different from that illustrated in the preceding figure, but said leads will be readily understood; and need not be more fully illustrated. This figure, however, will readily make clear to those skilled in the art how the propellers 16 may be placed on either side of the lifting planes at will.

In the modified form of connection shown in Fig. 7, a lever 60 is connected to the engine 16, and is provided with a gear or seg-

ment 61 meshing with an accompanying gear or segment 62 carried by the lever 63, pivoted as at 64 to the frame work 3, and from the lever 63 pass the cords 65 to the aviator's seat or arm rest 27, so that when one of the cords 65 is pulled, the lever 60 will be lowered and when the other cord 65 is pulled, the lever 60 will be raised.

Of course ball bearings, not shown, or other means may be employed to pivot the engines and the propellers, and also the position of the trunnions 13 are so chosen that all of the parts are balanced as near as possible, so as to lessen the amount of pull required of the aviator.

It is obvious that those skilled in the art may vary the details of construction, as well as the arrangement of parts, without departing from the spirit of my invention and therefore I do not wish to be limited to the above disclosure, except as may be required by the claims.

What I claim is:

1. In an aeroplane having a supporting surface, the combination of a frame work associated with said surface; a plurality of engines provided with shafts pivotally mounted to move up and down parallel to each other in said frame work; a propeller mounted on each shaft; a seat for an aviator; and connections between said engines and said seat, whereby the said aviator may readily tip each propeller in opposite directions relatively to said supporting surface to aid in stabilizing the machine; substantially as described.

2. In an aeroplane having a supporting surface, the combination of a frame work associated with said surface, a plurality of engines provided with shafts pivotally mounted in said frame work; levers extending from said engines; a propeller mounted on each shaft; a seat for an aviator; and connections between said levers and said seat, whereby the said aviator may readily tip each propeller in opposite directions relatively to said supporting surface to aid in stabilizing the machine, substantially as described.

3. In an aeroplane having a supporting surface, the combination of a frame work associated with said surface; a plurality of engines provided with shafts pivotally mounted to move parallel to each other in said frame work; a propeller mounted on each shaft; a lever extending from each engine; a seat for an aviator; and flexible connections between said levers and said seat, whereby the said aviator may readily tip each propeller in opposite directions and parallel to each other relatively to said supporting surface to aid in stabilizing the machine, substantially as described.

4. In an aeroplane having a supporting surface, the combination of a pair of en-

- gines located beneath said surface and at equal distances on each side of the center of buoyancy of the machine; means for pivotally mounting said engines; a propeller 5 connected to each engine; a movable member located near the aviator's seat; and flexible connections between said movable member and each engine, adapted to tip in opposite directions each engine and propeller 10 relatively to said supporting surface and in planes perpendicular thereto to aid in stabilizing the machine, substantially as described.
5. In an aeroplane having a supporting surface, the combination of a pair of engines located beneath said surface and at equal distances on each side of the center of buoyancy of the machine; means for pivotally mounting said engines to move in planes 15 perpendicular to said surface; a lever extending from each engine; a propeller connected to each engine; a movable member located near the aviator's seat; and flexible connections between said movable member 20
- and each lever, adapted to tip each engine 25 and propeller in opposite directions relatively to said supporting surface to aid in stabilizing the machine, substantially as described.
6. In an aeroplane the combination of a pair of supporting surfaces; a pair of engines pivotally mounted on each side of the center of buoyancy of said surfaces to move in planes perpendicular to said surfaces; propellers rigidly connected to said engines; 30 an aviator's seat having a pivoted back; levers extending from each engine; cords connected to said levers and pivoted back; and pulleys over which said cords pass whereby said propellers can only be moved in opposite directions to aid in stabilizing the machine, substantially as described.

In testimony whereof I affix my signature, in presence of two witnesses.

JAMES M. REYNOLDS.
